UNITED STATES PATENT OFFICE.

DAVID KENDALL, OF ALLIANCE, OHIO, ASSIGNOR TO THE ALLIANCE MACHINE COMPANY, OF ALLIANCE, OHIO, A CORPORATION OF OHIO.

CRANE.

1,226,533.

Specification of Letters Patent.

Patented May 15, 1917.

Application filed November 13, 1913. Serial No. 800,757.

To all whom it may concern:

Be it known that I, DAVID KENDALL, a citizen of the United States, residing at Alliance, in the county of Stark and State 5 of Ohio, have invented a new and useful Improvement in Cranes, of which the following is a full, clear, and exact description, reference being had to the accompanying drawings, forming part of this specification, in which—

Figure 1 is an end view of a gauntlet crane embodying my invention;

Figs. 2 and 3 are detail sectional views of the locking device, Fig. 3 being taken on 15 the line III—III of Fig. 2;

Fig. 4 is a view on a larger scale, partly in section and partly in elevation of the locking device;

Fig. 5 is a detail view of the automatic 20 cut-out and

Fig. 6 is a wiring diagram illustrating the electrical features of the invention.

My invention has relation to cranes, and more particularly to locking mechanism for 25 gauntlet cranes. In large structures of this kind, it has happened that by reason of high winds, the crane runs away and, owing to the high speed which it acquires, comes against the stops at the end of the crane 30 runway with sufficient force to overturn itself. For this and other reasons, it is desirable to provide means of simple and effective character by means of which the crane bridge may be instantly locked to the track.

35 My invention provides a device of this character which can be operated from the operator's cab. It also provides means for automatically controlling the operation of the locking device, and thereby stop the locking 40 motor after the brakes are released. The invention still further consists in the provision of means whereby the operator, after throwing the locking device into operation, is prevented from starting the motor which 45 controls the travel of the crane until he has first thrown such device out of operation.

The nature of my invention will be best understood by reference to the accompanying drawings, in which I have shown the 50 preferred embodiment thereof and which

will now be described, it being premised, however, that various changes may be made in the details of construction and arrangement of the parts, without departing from the spirit and scope of my invention, as defined in the appended claims.

In these drawings, the numeral 2 designates the bridge of a gauntlet crane, 3 the supporting legs thereof, 4 the track rails of the runway upon which the crane travels, 60 5 the motor for controlling the crane, and 6 the actuating gearing driven by the motor. 8 is the trolley mounted for travel on the bridge, and 9 is the operator's cage or cab. While in the present instance, this cage or 65 cab is carried by the trolley, it may be mounted on the bridge. The parts as thus far described are of the usual well known character and form no part of the present invention.

70 On one of the legs 3 of the crane, and preferably on the connecting cross bar 3^a thereof, I support a suitable frame 10, upon which is mounted an electric motor 11. The shaft of this motor is connected by the 75 pinion 12 and gear wheel 13 with a rotary shaft 14, which is suitably journaled on said frame. This shaft has threaded end portions 15, each of which engages a traveling nut 16, and these nuts are each provided 80 with trunnions 17, on which are mounted rollers 18, working between the top and bottom guides 19. The purpose of these rollers and guides is to constrain the motion of the nuts in a line substantially parallel to the 85 axis of the shaft 14, and also to provide for the thrust of the connecting bars 20. These bars 20 are loosely pivoted on the trunnions 17 and carry rods or shafts 21 at their lower ends upon which the brake shoes 22 are pivoted. These shoes are guided vertically by the guides 23.

When the motor 11 is in operation, the 90 two nuts 16 will be caused to travel toward each other, and consequently, the shoes 22 are moved downwardly with great force into contact with the track rails 4. Consequently, the entire crane bridge can not move without overcoming the great sliding friction between these shoes and the rail, and 100

this friction is sufficient to prevent movement of the bridge under the heaviest wind pressures.

The motor 11 may be controlled in any suitable way. I prefer, however, to locate the controller in the operator's cage, so that he can lock the crane in position whenever he leaves the crane cab, and thus leave the crane in a safe condition. This is illustrated by the wiring diagram of Fig. 7. In this particular diagram, both the bridge motor 5 and the locking motor 11 are operated by master controllers located in the crane cab and by magnetic controllers located near the motors. This, however, is not essential, as the crane may be operated by means of ordinary controllers located entirely in the cab. In this diagram, *a a* designate the main feed wires, *b b* the bridge wires, and *c c* the locking wires. M C is the master controller for the bridge motor, and M' C' is the master controller for the locking motor 11. C is the magnetic controller for the bridge motor and C' is the magnetic controller for the locking motor. These master controllers are located in the cab. The details of these controllers, together with the details of the controllers C C' form no part of the present invention, since any suitable type of controller may be employed. Therefore, they will not be described in detail.

The solenoid switches of the controller C' in the power circuits of the motor 11 are normally open. By throwing the master controller M' C' to the right or left, one or the other of the solenoid switches is energized and closed, to drive the motor in a direction to apply or release the brakes.

In order to stop the locking motor 11 when the brakes have been released, I provide a cut-out for the locking motor. This cut-out is shown as consisting of a pivoted lever 24. Journaled to one arm of the lever 24 is a track roller 26. The opposite arm 45 has a contact 27 which when the track roller 26 is disengaged is held against the fixed contact 28 by means of a compression spring 25. The contact 27 is connected through the controller C', while the contact 50 28 is connected through the master controller M' C', as shown in Fig. 6. 29 is a bar which is secured to one of the nuts 16 in position to be arranged to be engaged by the roller 26 and has a downwardly bent end 55 30. When this nut travels far enough away from the center to release the locking shoe 22, the bar 29 moves under the roller 26, lifting it and separating the contacts 27 and 28. This opens the circuit through the master 60 controller M' C' and the motor controller C' and stops the motor 11.

As thus far described, it is possible for the operator to set the locking device and leave the crane, say for the night, and re-

turn to the crane the following morning and attempt to start it without releasing the locking device. To prevent this, I preferably provide a cut-out device which will automatically break the circuit of the bridge motor master controller M C when the lock 70 is set, and thus render it impossible for the operator to start said motor 5, without first releasing the lock. This may be done in various ways. In the arrangement shown, the bar 29 is provided with a downwardly bent 75 portion 31, at the opposite end from the portion 30. A second lever arm 32 is provided, said arm having a contact wheel 33 and a spring 34. The lever also carries a contact 35, which is normally held by the 80 spring in engagement with the relatively fixed contact 36. The circuit of the bridge motor master controller M C is normally completed through these contacts 35 and 36. When, however, the locking device is set, 85 the movement of the bar 29 causes its bent end portion 31 to engage the contact roller 33, and thus separate the contacts 35 and 36. This breaks the circuit of the motor master controller M C and the bridge motor 5 90 can not be operated until the locking device has been released.

The advantages of my invention will be apparent to those familiar with the operation of this class of cranes, since it provides a 95 means of extremely simple and effective character by which a gauntletree crane can be instantly locked to its runway and held safely in this locked position. This is preferably, although not necessarily, accomplished from the operator's cab. The provision of means for automatically stopping the movement of the locking device when it is released and the provision of the automatic cut-out for the bridge motor is also 100 extremely advantageous.

I claim:

1. A gauntletree crane having a motor mounted thereon, a shaft driven by said motor, traveling nuts engaged by said shaft, substantially vertically movable track engagement brake shoes connected to said nuts, and guiding means for the brake shoes, substantially as described.

2. The combination with a gauntletree crane, of a motor mounted thereon, a shaft geared to said motor, traveling members engaged by said shaft, guiding means for said members, and friction locking devices connected to the traveling members and movable into and out of holding engagement with the crane runway; substantially as described.

3. A gauntletree crane having a motor mounted thereon, a shaft geared to said motor, traveling nuts engaged by said shaft, guides for the said nuts, depending bars connected to the nuts, and brake shoes carried by the bars and movable toward and

away from the crane runway and into and out of braking engagement therewith; substantially as described.

4. The combination with a gauntlet crane having a propelling motor, of a safety locking device carried by the crane for locking it in stationary position on its runway, means for automatically limiting the movement of the locking device in one direction 10 and means controlled by said device to auto-

matically open the circuit of the propelling motor when the locking device is in operative position; substantially as described.

In testimony whereof, I have hereunto set my hand.

DAVID KENDALL.
